UNITED STATES PATENT OFFICE

161,968

APRON

Lenore D. Sinay, Long Beach, Calif.

Application April 7, 1950, Serial No. 9,040

Term of patent 14 years

(Cl. D3—26)

To all whom it may concern:

Be it known that I, Lenore D. Sinay, a citizen of the United States of America, residing in the city of Long Beach, in the county of Los Angeles, State of California, have invented a new, original, and ornamental Design for an Apron, of which the following is a specification, reference being had to the accompanying drawing, forming a part thereof.

I claim:

The ornamental design for an apron, substantially as shown.

LENORE D. SINAY.
